UNITED STATES PATENT OFFICE

93,971

DESIGN FOR A NOVELTY DOOR STOP

Leonard Clark, Dundas, Ontario, Canada

Application August 13, 1934, Serial No. 52,933

Term of patent 3½ years

To all whom it may concern:

Be it known that I, LEONARD CLARK, a subject of the King of Great Britain, residing at the town of Dundas, in the county of Wentworth, in the Province of Ontario, Canada, have invented a new, original, and ornamental Design for a Novelty Door Stop, of which the following is a specification, reference being had to the accompanying drawing, forming part thereof.

Fig. 1 is a front view of a novelty door stop, showing my new design, and

Fig. 2 is a side view thereof.

I claim:

The ornamental design for a novelty door stop, as shown.

LEONARD CLARK.
